UNITED STATES PATENT OFFICE.

WILLIAM C. HUEBNER, OF BUFFALO, NEW YORK, ASSIGNOR TO HUEBNER-BLEISTEIN PATENTS COMPANY, OF BUFFALO, NEW YORK.

PHOTOGRAPHIC-PRINTING APPARATUS.

1,109,289.

Specification of Letters Patent.

Patented Sept. 1, 1914.

Application filed August 28, 1911. Serial No. 646,374.

To all whom it may concern:

Be it known that I, WILLIAM C. HUEBNER, a citizen of the United States, residing at Buffalo, in the county of Erie and State 5 of New York, have invented a new and useful Improvement in Photographic-Printing Apparatus, of which the following is a specification.

This invention relates to apparatus or 10 machines for producing single or repeated photographic prints or designs upon sensitized plates or stones which are afterward finished in any suitable manner for printing in one or more colors, such apparatus or 15 machines comprising a holder for the sensitized plate or stone, a light chamber which is arranged opposite the sensitized surface and which carries a transparent negative or positive which is pressed against the sensitized 20 surface, and a back support or pressure device which bears against the rear side of the plate or stone for producing a close and uniform contact of the positive or negative with the sensitized surface, the parts being 25 adjustable in such manner that the print or design can be produced upon any desired portion of the sensitized surface.

The object of this invention is to produce 30 a machine of this character in which the adjustable parts are mounted in a novel and desirable manner for placing the sensitized surface in the printing position quickly and accurately.

The accompanying drawings show two 35 different styles of apparatus embodying the invention, a horizontal apparatus in which the sensitized plate or stone lies horizontally and the light chamber and pressure device are arranged respectively below and 40 above the same; and a vertical apparatus in which the sensitized plate or stone stands vertically and the light chamber and pressure device stand on opposite sides thereof.

Figure 1 is a sectional elevation of the 45 horizontal apparatus on line 1—1, Fig. 2. Fig. 2 is a sectional elevation thereof on line 2—2, Fig. 1. Fig. 3 is a fragmentary elevation of the adjusting mechanism. Fig. 4 is a sectional plan view of the apparatus 50 on line 4—4, Fig. 1. Fig. 5 is a plan partly in section thereof on line 5—5, Fig. 1, showing a different adjustment of the parts. Fig. 6 is an end elevation of the vertical apparatus. Fig. 7 is a sectional elevation 55 thereof on line 7—7, Fig. 8. Fig. 8 is a side

elevation partly in section thereof. Fig. 9 is a sectional plan thereof on line 9—9, Fig. 8.

Like reference characters refer to like parts in the several figures.

Referring first to the horizontal apparatus shown in Figs. 1—5, A represents the lower portion of the stationary main frame which, as shown, is of circular skeleton form and is surmounted by an upright yoke *a* connecting opposite sides thereof. B represents the sensitized plate which is secured in a holder C. The latter consists of a rectangular frame provided at opposite ends with clamps *c* *c'* for engaging opposite ends of the plate. One of the clamps is movable toward and from the other for securing and stretching the sensitized plate by screws *c*² on one end of the holder, which screws are operated by a chain *c*³ passing around wheels on the adjusting screws and an operating wheel *c*⁴ adapted to be turned by any suitable means. The plate holder C is removably supported in stationary horizontal guides D on opposite sides of the yoke *a* of the main frame. The holder can be slipped horizontally into and out of the guideway. The light chamber E and the pressure device or back support F, which may be of any suitable construction, are arranged respectively below and above the plate holder C and can be adjusted horizontally to place them opposite any desired portion of the sensitized plate. They can also be moved vertically toward and from the sensitized plate to make contact with the plate and to retract them therefrom. The light chamber has a transparent top or face plate *e*² on which the transparent positive or negative printing plate *e* is secured and is provided with electric lamps *e'* for illuminating the printing plate to produce the photographic print. The light chamber is mounted on a carriage G which is swiveled centrally at *g* on a slide *g'* arranged to be adjusted in a horizontal guide-way or track *g*² extending diametrically across a supporting frame H which is arranged to turn horizontally on a center bearing *h* in the lower portion of the stationary frame A. The carriage slide *g'* is adjusted radially in its guide-way *g*², by any suitable means, for instance, an adjusting screw I journaled on the rotatable supporting frame H, and the latter is rotatably adjusted by any suitable means, for instance, 105 110

by a crank shaft K provided with a pinion k meshing with a toothed rack k' on the frame H. The rotary adjustment of the frame H is indicated by a pointer k² on the adjusting frame coöperating with a scale k³ on the main frame, see Fig. 4. The light chamber can thus be adjusted radially on the rotatable frame toward and from the axis thereof and also in an arc concentric with the axis of the 5 rotatable frame H by turning the latter, whereby the light chamber can be moved to any position relative to the sensitized surface within the range of said radial and rotary adjustments. The light chamber is so 10 mounted that it retains in all of its adjusted positions a position parallel to a given line, in order that the prints may always be made on the sensitized surface in an upright position, or in a position parallel to such line. 15 For instance, the side line of the light chamber may be kept parallel with the side line of the sensitized surface. This may be accomplished by parallel shafts L L which extend through bearings l on opposite ends of 20 the carriage G and are journaled at their ends in bearings l' l² adapted to slide on parallel horizontal rods or shafts l³ l⁴ mounted on the stationary main frame at right angles to the shafts L L. Since the 25 carriage G is free to swivel on the slide g' and to slide on the guide shafts L L and the guide shafts L L are free to slide on the guide rods or shafts l³ l⁴, these shafts permit the carriage of the light chamber to be 30 adjusted radially on the supporting frame and to turn with the supporting frame and at the same time remain parallel with the edges of the sensitized plate B. The light chamber is movable vertically toward and 35 from the sensitized plate on guide pins m on the carriage G and is provided at opposite ends with toothed racks m' meshing with pinions m² which are so connected with the shafts L L that they turn with the same, 40 but can slide thereon with the carriage G. The shafts L are connected by bevel pinions m³ m⁴ to the shaft l³ so that by turning this shaft by a crank l⁵, or otherwise, the shafts L L are rotated simultaneously for moving 45 the light chamber into and out of contact with the sensitized surface. The bevel pinions m⁴ are journaled on the bearings l' for the shafts L L and are connected with the shaft l³ so that they can slide thereon in the 50 adjustments of the light chamber. l⁶, Fig. 4, represents a ratchet and dog for holding the light chamber when moved into contact with the sensitized plate. The pressure device F, or back support, consists of a padded 55 block which is arranged above the holder for the sensitized plate and, like the light chamber, is mounted on a carriage swiveled on a slide which is adjustable in a diametrical guide-way on a horizontally rotatable 60 supporting frame. N represents the carriage, n the slide, n' the guide-way therefor, and O the rotatable supporting frame. The latter turns on a center bearing o on the yoke a of the main frame and is rigidly connected to the rotatable frame H to turn therewith, as by a frame o' at one side thereof. The frames H and O thus constitute, in effect, a single rotatable support for the light chamber and pressure device. The carriage slide n is adjusted radially, preferably by a screw P journaled on the rotatable frame O. The pressure device is retained with its edges parallel with the edges of the sensitized plate or surface in the same manner as the light chamber, by parallel shafts 75 Q Q which extend through bearings on opposite ends of the carriage N and are journaled at their ends in bearings q' q² adapted to slide on parallel horizontal rods or shafts q³ q⁴ on the main frame. The pressure device is movable toward and from the sensitized plate on guide pins r on the carriage N and is moved by pinions r' on the shafts Q Q engaging with toothed racks r² on the pressure device. The shafts Q Q are 80 connected by bevel pinions r³ r⁴ to the shaft q³ so that the shafts Q Q are turned simultaneously for moving the pressure device into and out of contact with the sensitized plate by turning the shaft q³. q⁵, Fig. 5, 85 represents a ratchet and dog for holding the pressure device when moved into contact with the sensitized plate. The adjusting screws I and P are turned simultaneously for correspondingly adjusting the light chamber and the pressure device, for instance, by a connecting shaft s which is geared by bevel pinions s' s' to the adjusting screws I and P and by bevel wheels s² s³ to an electric motor S mounted on the rotatable frame H. 90 In order to provide a very exact or fine adjustment of the light chamber and pressure device, the adjusting mechanism therefor is preferably controlled by an automatic electrical controller which is indicated at T. 100 The construction of this controller is not herein claimed and is, therefore, not described. It is constructed and operates as fully disclosed in my application Serial No. 619,560, filed April 7, 1911. The mechanical features of the mechanism for adjusting the light chamber and pressure device or the rotatable frames and for turning the rotatable frames can be modified in various ways 105 without departing from the invention. 110 Referring now to the vertical apparatus shown in Figs. 6-9, the arrangement and adjustments of the light chamber and pressure device with reference to the sensitized plate or surface is substantially the same as 115 in the horizontal apparatus, except that the holder for the sensitized plate or part is arranged vertically and the light chamber and pressure device are movable horizontally into and out of contact with the sensitized 120 125 130

plate and are adjustable in vertical planes parallel with the sensitized surface for placing them opposite to any desired portion of the sensitized surface. B' represents the sensitized plate or part and C' the holder therefor which is removably supported in upper and lower horizontal guides D' on the main frame A'. The sensitized plate is stretched in the holder, as in the other holder described, by screw operated clamps actuated by a chain e¹³, Fig. 8. The light chamber E' is mounted on a carriage G' which is swiveled on a slide g¹¹ adapted to be adjusted in a diametrical guide-way g¹² on a supporting frame H' which is arranged to turn vertically in upper and lower bearings h¹⁴ and h¹⁵ on the stationary main frame. The light chamber is held with its edges parallel to the edges of the sensitized plate by parallel vertical shafts L' L' which extend through bearings at the opposite ends of the carriage G' and are journaled at their ends in bearings l¹¹ l¹² adapted to slide on upper and lower horizontal rods or shafts l¹³ l¹⁴ on the main frame. The light chamber is movably supported on the carriage G' and is moved horizontally toward and from the sensitized plate or surface by screws l¹⁵ secured to the light chamber and working in internally threaded pinions l¹⁶ which are journaled on the carriage G' and mesh with pinions l¹⁷. These pinions l¹⁷ are splined on the shafts L' L' so that they turn with the shafts and are adapted to slide thereon with the carriage G'. The shafts L' are turned simultaneously for moving the light chamber toward and from the sensitized plate by bevel pinions l¹⁸ thereon meshing with bevel pinions l¹⁹ which are splined on the lower horizontal shaft l²⁰ which is adapted to be turned by a crank l²¹ applied to the end thereof, as indicated by the dotted lines in Fig. 8. The pressure device F' is similarly mounted on a carriage N' which is swiveled on a slide n¹¹ adapted to be adjusted in a diametrical guide-way n¹² on a supporting frame O' which is arranged to turn vertically in upper and lower bearings o¹¹ o¹² on the main frame. The frame O' is rigidly connected to the frame H' to turn therewith, for instance by a cross piece o¹³. The pressure device is retained with its edges parallel with the edges of the sensitized plate or surface by parallel vertical shafts Q' Q' which extend through bearings on the opposite ends of the carriage N' and are journaled at their ends in bearings q¹¹ q¹² adapted to slide on horizontal rods or shafts q¹³ q¹⁴ on the stationary frame. The pressure device is movably supported on the carriage N' and is moved horizontally toward and from the sensitized plate or surface by screws q¹⁵ operated by pinions q¹⁶ which mesh with pinions q¹⁷ splined on the shafts Q'. The shafts Q' are turned simultaneously for mov-

ing the pressure device toward and from the sensitized plate by gears (not shown) connecting them with one of the horizontal shafts q¹³ q¹⁴. The supporting frames H' and O' are rotatably adjusted by any suitable means, such, for instance, as shafts V V' provided with worms v meshing with worm wheel segments v' secured to the rotatable frames H' and O'. One of the shafts, V, is adapted to be turned, for instance, by an operating shaft v² geared thereto by wheels v³ and adapted to receive a crank on its end, and the other shaft, V, is caused to turn with the operating shaft v² by a cross shaft v⁴ and bevel pinions v⁵ and v⁶. The rotary adjustment of the frames H' and O' can be indicated by a graduated wheel v⁷ geared to the operating shaft v² and a co-operating pointer v⁸. The slides for the light chamber and pressure device carriages are simultaneously adjusted radially in their guide-ways on the rotatable supporting frames H' and O', preferably by screws W' and W which are journaled on the rotatable frames and are connected by bevel pinions w to a shaft w' which is geared to and driven by an electric motor w² mounted on the connecting cross-piece for the rotatable frames. X represents a controller similar to the controller T, for regulating the radial adjustment of the light chamber and pressure device on the rotatable supporting frame.

The operation of the horizontal apparatus is as follows: After the sensitized plate B has been properly stretched in the holder C and the latter placed in its guides D, and the transparent printing plate e secured on the light chamber, the light chamber E and the pressure device F are adjusted circumferentially and radially by the described mechanism, so as to place the printing plate in position to make the print in the desired location on the sensitized surface. The light chamber and pressure device are then moved toward the sensitized plate as described to press the printing and sensitized plates into contact, after which the lights are turned on to make the print. The light chamber and the pressure device can then be manipulated as before to make successive prints in any desired arrangement or positions on the sensitized surface, or impressions from the same or different printing plates can be made in corresponding or other desired positions on the same or successive sensitized plates.

The operation of the vertical apparatus is substantially the same as that of the horizontal apparatus.

The apparatus illustrated and described is intended for printing on the sensitized surfaces of thin metal plates or sheets and the pressure device is used to afford a rigid backing for the sensitized plate or sheet. The holder C or C' could, however, be read-

ily adapted for supporting a rigid part having a sensitized surface, such as a lithographic stone. In such case the pressure device would not be required and only the 5 light chamber would be mounted and adjusted as described.

I claim as my invention:

1. The combination of a device for holding a sensitized part, a photographic device 10 for producing a print upon the sensitized part, one of said devices being adjustable with reference to the other, adjusting means for said adjustable part capable of circular movement in a plane parallel with the surface 15 of said sensitized part, and guiding means for maintaining said adjustable part in positions which are parallel with each other in the different adjustments of said part.
2. The combination of a holder for a sensitized part, a photographic device for producing a print upon the sensitized part, an adjusting device for said photographic device capable of circular movement in a plane 25 parallel with the surface of said sensitized part, and a guiding device which maintains said photographic device in positions which are parallel with each other in the different adjustments of said photographic device.
3. The combination of a holder for a sensitized part, a light chamber opposite said sensitized part for illuminating a photographic printing plate, an adjusting device for said chamber capable of circular movement in a plane parallel with the surface of 35 said sensitized part, and guiding means for maintaining said chamber in positions which are parallel with each other in the different adjustments of said chamber.
4. The combination of a light chamber for illuminating a photographic printing plate, a pressure device, a holder for supporting a sensitized part between said light chamber and said pressure device, an adjusting device 45 for said pressure device capable of circular movement in a plane parallel with the surface of said sensitized part, and guiding means for maintaining said pressure device in positions which are parallel with each other 50 in the different adjustments of said pressure device.
5. The combination of a light chamber for illuminating a photographic printing plate, a pressure device, a holder for supporting a sensitized part between said light chamber and said pressure device, adjusting devices 55 for said light chamber and said pressure device capable of circular movement in planes parallel with the surface of said sensitized part, and guiding means for maintaining said chamber and said pressure device each in positions which are parallel with each other in the different adjustments 60 of said chamber and pressure device.
6. The combination with a holder for a sensitized part, a support capable of circular adjustment in a plane parallel with the surface of said sensitized part and provided with a diametrical guide, a slide which is adjustable on said guide toward and from the center of rotation, and a carriage for a light chamber or a pressure device pivotally connected with said slide. 70
7. The combination of a holder for a sensitized part, a support capable of circular adjustment in a plane parallel with the surface of said sensitized part and provided with a diametrical guide, a slide which is adjustable lengthwise on said guide, a carriage for a light chamber or a pressure device 80 pivotally connected with said slide, and means whereby said carriage is movable in said slide toward and from said holder. 85
8. The combination of a holder for a sensitized part, a support capable of circular adjustment in a plane parallel with the surface of said sensitized part and provided with a diametrical guide, a slide which is adjustable lengthwise on said guide, and a carriage for a light chamber or a pressure device 90 pivotally connected with said slide, and provided with a guide which is arranged parallel with the axis of said pivotal connection and adapted to carry a light chamber or a pressure device. 95
9. The combination of a holder for a sensitized part, a support capable of circular adjustment in a plane parallel with the surface of said sensitized part and provided with a diametrical guide, a carriage for a light chamber or a pressure device which is 100 adjustable on said guide toward and from the center of rotation and which is pivotally supported thereon, and a guide which maintains said carriage in positions which are 105 parallel with each other in the different adjustments of said carriage.
10. The combination of a holder for a sensitized part, a support capable of circular adjustment in a plane parallel with the surface of said sensitized part and provided with a diametrical guide, a carriage which is adjustable on said guide toward and from the center of rotation and which is pivotally supported thereon, a light chamber which is 110 movable on said carriage toward and from said sensitized part, and mechanism for so moving said light chamber on said carriage, such mechanism comprising a guide shaft which maintains said light chamber in positions which are parallel with each other in the different adjustments of said light chamber. 115
11. The combination of a holder for a sensitized part, supports for a light chamber 120 and a pressure device arranged on opposite sides of said holder and capable of circular adjustment, diametrical guides on said supports, carriages which are adjustable on said guides toward and from the center of rotation. 130

- tion and which are pivotally supported thereon, a light chamber which is movable on one of said carriages toward and from the sensitized surface, a pressure device which is movable on the other carriage toward and from the rear side of said sensitized part, and guides for maintaining each of said carriages in positions which are parallel with each other in the different adjustments of said carriage.
12. The combination of a holder for a sensitized part, a support capable of circular adjustment in a plane parallel with the surface of said sensitized part, a carriage capable of radial adjustment on said support, a light chamber and means whereby said light chamber is adjustable on said carriage toward and from the sensitized surface.
13. The combination of a holder for a sensitized part, a support capable of circular adjustment in a plane parallel with the surface of said sensitized part, a carriage capable of radial adjustment on said support, a pressure device, and means whereby said pressure device is adjustable on said carriage toward and from said sensitized part.
14. The combination of a holder for a sensitized part, a support capable of circular adjustment in a plane parallel with the surface of said sensitized part, a carriage capable of radial adjustment on said support and pivotally connected therewith, a light chamber adjustable on said carriage toward and from said sensitized part, and guide shafts and guide rods arranged at right angles to each other and forming part of the adjusting mechanism of said chamber.
15. The combination of a holder for a sensitized part, a support capable of circular adjustment in a plane parallel with the surface of said sensitized part, a carriage capable of radial adjustment on said support and pivotally connected therewith, a pressure device adjustable on said carriage toward and from said sensitized part, and guide shafts and guide rods arranged at right angles to each other and forming part of the adjusting mechanism of said pressure device.
16. The combination of a holder for a sensitized part, a light chamber for illuminating a photographic printing plate, a support for said chamber capable of circular adjustment in a plane parallel with the surface of said sensitized part, and means for adjusting said chamber on said support toward and from the center of rotation. 50
17. The combination of a light chamber for illuminating a photographic printing plate, a pressure device, a holder for supporting a sensitized part between said light chamber and said pressure device, a support for said pressure device capable of circular adjustment, and means for adjusting said pressure device on said support toward and from the center of rotation. 60
18. The combination of a light chamber for illuminating a photographic printing plate, a pressure device, a holder for supporting a sensitized part between said light chamber and said pressure device, supports for said light chamber and pressure device capable of circular adjustment, and means for rotating both supports simultaneously. 70
19. The combination of a light chamber for illuminating a photographic printing plate, a pressure device, a holder for supporting a sensitized part between said light chamber and said pressure device, supports for said light chamber and pressure device capable of circular adjustment, means for rotating both supports simultaneously, and mechanism for adjusting the light chamber and the pressure device on said supports toward and from the center of rotation. 80 85

Witness my hand this 21st day of August, 1911.
